Patented Apr. 25, 1922.

Invantor.
Luis Santana,
By: B. Amigo, Atty.

UNITED STATES PATENT OFFICE.

LUIS SANTANA, OF TRINIDAD, CUBA.

CIGAR-MAKER'S KNIFE.

1,414,098.

Specification of Letters Patent. Patented Apr. 25, 1922.

Application filed October 16, 1919. Serial No. 331,236.

To all whom it may concern:

Be it known that I, LUIS SANTANA, a citizen of the Republic of Cuba, and a resident of Trinidad, Province of Santa Clara, Cuba, 5 (whose post-office address is Capdevila Street Number 47, Trinidad, Province of Santa Clara, Cuba,) have invented certain new and useful Improvements in Cigar-Makers' Knives, of which the following is 10 a specification.

This invention relates to knives used by cigar makers in the manufacture of cigars; and its object is to provide a cigar-maker's knife of improved construction which affords an easy bearing to the user without 15 injuring the palm of the hand, which may be firmly mounted between the fingers and prevented from slipping out of the hand, another object is also to provide an improved cigar-maker's knife embodying a 20 blade which may be easily replaced for a new one, once the former has been worn out. This cigar-maker's knife also has the advantage of producing better and quicker cuts 25 owing to the uniformity of its shape relatively to the common knife at present in use which is of irregular shape.

The invention is described with reference to the figures of the annexed drawing, in 30 which:

Fig. 1 is a front view of my improved cigar-maker's knife with the blade in place.

Fig. 2 is a cross-section on line 2—2 of Fig. 1.

Fig. 3 is a front view of the same with the blade removed.

Fig. 4 is a cross section on line 4—4 of Fig. 3.

Fig. 5 is a detail elevation of the blade. 40 My improved cigar-maker's knife comprises a metal plate 1 of the common shape in this class of instruments; that is to say, it is segmental in form, its upper edge is convexly curved and its lower edge is also 45 convexly curved. At the upper edge of the plate is a flange 2 which projects from one side of the plate, is nearly tubular and is formed integrally with the plate as shown.

The ends of said flange terminate short of 50 the lower corners of the plate, so that the lower portion of the plate is unobstructed. At its lower edge 1" said plate 1 has a re-

cess 3 of certain depth, which is longitudinally extended in said edge and terminates at a short distance from the ends of the said 55 edge, leaving there solid end portions 3' and within said recess 3 is lodged nearly to a third of its width a steel knife 4 of arched shape similar to inner edge 1" of plate 1' and which is provided at its ends with rectangular cuts 5 at its upper half to fit edge-wise with the solid portions 3' limiting the recess 3 of plate 1. The knife 4 can be lodged by pressure within the slot 3 or it can be secured inside thereof by means of 60 65 bolt screws passing across same and the plate 1.

Plate 1 constitutes a support for the knife 4 which can be replaced by a new one when the former is worn out or made unfit for 70 being used. In practice, the user holds the cigar-maker's knife with the hand in such manner that the flange 2 may be at the outside with respect to him, and this flange 2 will serve as an easy and ample bearing for 75 the fore finger and for the palm of the hand, aiding the pressure of the fingers and the resting of the hand thereon, thus preventing the cramping thereof, as well as preventing the formation of callous thereon and 80 the cutting of the palm of the hand owing to the sharp edge of the back of the knife, as is liable to occur with the cigar-makers' knives at present in use. The flange also serves as a retaining means for the middle 85 finger bearing against the outer face of the plate 1, thus preventing it from sliding out of said plate and the knife from slipping out of the hand. Since the inner face of the cigar-maker's knife is plain and smooth, 90 it permits the user to iron up the cigar made with the same instrument.

It is obvious that the form of the blade and of the supporting plate thereof, as well as of the upper flange and the means for 95 securing the blade to the plate can vary without altering the spirit of the invention which is as pointed out in the appended claims.

What I claim is:—

1. A cigar maker's knife comprising a flat plate having convex upper and lower edges, and also having a correspondingly curved flange at the upper edge, on one side of the 100

plate, and a curved blade fitted to the lower portion of the plate and extending below the lower edge thereof.

2. An improved cigar-maker's knife comprising a supporting plate provided with an inturned flange at its upper edge which projects towards the outer face of the knife and

having a longitudinally extended recess at its lower edge, and a blade for replacement lodged in said recess with its cutting edge 10 projecting therefrom.

In witness whereof I affix my signature.

LUIS SANTANA.
